TOOL HANDLES

Carlton L. Whiteford, San Juan, Puerto Rico
Application June 9, 1955, Serial No. 514,237

5 Claims. (Cl. 145—61)

A conventional screwdriver, which consists of a tool comprising a handle, generally of wood, and a steel blade fixed therein, has many uses besides the insertion and withdrawal of screws. In one of its more common uses it is employed with a hammer to drive the blade into articles, such as shipping crates and wooden boxes, to pry them open; and when so used the hammer action on the end of the handle tends to split the handle, or if the latter is of a resilient plastic composition, to drive the blade into and sometimes entirely through the handle. The fact that so many handles are thus injured or destroyed has led to a U. S. governmental regulation that screwdrivers purchased for use by the Army or Navy must be capable of meeting a so-called "impact test" conducted at room temperature. That test is as follows:

The blade end of each screwdriver shall be mounted vertically in a vise affixed to the base of a suitable falling weight impact device. The blade tip shall rest on a solid surface to insure that the blade does not move vertically in the vise. The weight shall be 15 pounds, cylindrical in shape, and shall be dropped through a piece of seamless tubing slightly larger than the diameter of the weight in order to insure that the full force of the falling weight will be acting normal to the striking surface. The screwdriver handle shall not break, crack, or significantly distort, nor shall the blade penetrate more than $\frac{5}{8}$ inch into the handle when the weight has been dropped ten times from the heights listed below. Significantly distort (for purpose of this test) means an increase of at least 3 percent in the handle diameter, either of a uniform or irregular bulge. In conducting this test, care should be taken that the impact energy shall not be expended in flexing of the blade or in driving the screwdriver tip into the surface on which it rests. The blade shall be shortened or blunted, if necessary, to insure a proper test.

Blade diameter: $+\frac{3}{64}$ -0.010	Height of drop of 15-pound weight for impact test
Inches	Inches
$\frac{1}{8}$	$1\frac{1}{2}$
$\frac{9}{32}$	$2\frac{1}{4}$
$\frac{9}{16}$	6
$\frac{7}{32}$	8
$\frac{1}{4}$	10
$\frac{9}{64}$	12
$\frac{5}{16}$	15
$1\frac{1}{32}$	17
$\frac{3}{8}$ and over	20

The object of this invention is to provide screwdrivers or other tools having steel blades and plastic handles capable of meeting the foregoing test.

In the accompanying drawings, Fig. 1 is a view in central longitudinal section of a conventional screwdriver, from which its blade has been removed; Fig. 2, a similar view of the same but showing a plastic handle with the shank of the blade in its normal position within the handle; and Fig. 3, a similar view of my improved

2

plastic handle with the shank of the blade inserted and held therein.

- The shank 10 of the blade 11 will generally be cylindrical in shape to fit tightly in a similarly shaped bore or socket 13 of the handle and, if desired, may be provided with ears (not shown) projecting from its rounded surface to prevent it from turning in the handle. The handle assembly comprises two separately molded pieces of resilient plastic material 14 and 15 respectively.
- 5 10 The piece 14 which constitutes the handle proper is produced from a resilient plastic material which, at any temperature between 100 and -20° F., has high impact strength and elasticity so as to be momentarily deformable under high impact, and for which purpose such plastic materials as nylon, ethyl cellulose, cellulose acetate and cellulose acetate butyrate, may be used, for example, in practicing my invention. The other piece 15 of the handle assembly consists of a plug having a free fit with the inner end of the bore or socket 13; and by free fit 15 20 I means that while its rounded surface contacts the inner surface of the bore, it does not, like the shank of the blade, fit the bore tightly. The inner end of said plug abuts against the inner end of said bore; and the end of the blade-shank abuts against the other end of said plug.
- 25 20 Both the handle proper 14 and the plug 15 may be molded from the same material provided the latter has the properties aforesaid; but for reasons of economy in manufacture I may, for example, mold the handle proper 14 from the relatively less expensive cellulose acetate and the plug 15 from nylon which has the relatively greater impact strength.

30 After the aforesaid test has been applied to a screwdriver having a handle constructed as hereinbefore described, an examination of the screwdriver will show no measurable penetration of the blade into the handle beyond its original position in the handle, nor any bulge or increase in the handle diameter, although during the test it will be possible to detect a temporary increase in diameter upon each impact, due to the slight expansion 35 40 of the plug 15 which is indicated by the dotted lines in Fig. 3.

The manner in which the material of the handle assembly responds to each hammer blow on the end of the handle can be the more readily understood if it be assumed that the plug 15 be removed and the place occupied by the plug be filled with a non-compressible liquid, such as oil, and then sealed so that none of the liquid can escape. In such a case, the force of each hammer blow on the end of the handle imparts to the 45 50 confined liquid a potential energy, the total amount of which would expend itself not merely against the rear end of the bore or socket 13, but would be evenly distributed over the entire surface of the surrounding plastic material of the handle proper 14, with the result that the handle would slightly expand with each blow and then almost immediately contract to its normal dimensions. Since the solid material of the plug is resilient and thus momentarily deformable under high impact, it can be regarded as "flowing" at the moment of impact; and, 55 60 therefore, that the hydraulic principle that liquids under pressure transmit their energy in all directions applies to explain the reaction of my screwdriver to the impact test aforesaid.

In exploiting my invention, I am at present selling my 65 improved handle assemblies separate from the blades, and which the purchasers thereof use in the manufacture of screwdrivers by inserting blades of their own manufacture into these handle assemblies.

I claim as my invention:

70 1. A tool having a steel blade and a handle therefor of a resilient material containing a dead end bore in which the blade is held, the blade having a shank por-

tion which is substantially similar in shape and size to the bore, so as to fit tightly in the bore, the inner end of the shank being spaced from the inner end of the bore, in combination with a flowable material filling the space in said bore between the end of the blade and the inner end of the bore. 5

2. In a tool having a steel blade and a handle therefor of a resilient plastic material of high impact strength and elasticity and having a dead end bore in which the shank of the blade is held, the shank being substantially 10 similar in shape and size to the bore, and fitted tightly in the bore, the combination with the blade and handle of a plug also of a resilient plastic material of high impact strength and elasticity freely fitted to and within the bore of the handle and against which the blade abuts. 15

3. The combination of claim 2 in which said plug is of the same plastic material as the said handle.

4. The combination of claim 2 in which the handle is of cellulose acetate and the plug of nylon.

5. A tool having a blade and a handle of resilient plastic material containing a dead end bore in which one end of the blade is held, the bore and the end of the blade held thereby being substantially similar in trans- 20

verse shape and size and so that the blade is held by a tight fit in the bore, in combination with a solid plug of resilient plastic material which is substantially similar in transverse shape and size to the bore and the aforesaid end of the blade and which is fitted in the bore between, and in engagement with, the end of the blade and the inner end of the bore.
